UNITED STATES PATENT OFFICE.

JUSTIN GILBERT, OF VICTORIA, BRITISH COLUMBIA, CANADA.

FOUNTAIN-PEN.

1,161,123.

Specification of Letters Patent. Patented Nov. 23, 1915.

Application filed August 13, 1913. Serial No. 784,555.

To all whom it may concern:

Be it known that I, JUSTIN GILBERT, a subject of the King of Great Britain, residing in the city of Victoria, Province of 5 British Columbia, Canada, have invented certain new and useful Improvements in Fountain-Pens, of which the following is a specification.

In the use of fountain pens considerable 10 objection has been found from the fact that they are subject to leakage due to a number of causes, among which may be mentioned the position of the pen, atmospheric conditions, and the heat of the hand in holding 15 the pen; another objection to the usual type of fountain pen is that they are opaque and consequently the user cannot determine when the pen needs refilling until he is apprised of that fact by the failure of the pen 20 to write.

The object of my invention is to overcome these objections and it consists first, in a 25 vacuum chamber applied to that portion of the wall of the main barrel which adapts it to separate the overlying portion of the user's hand from the ink reservoir, and prevent the conduction of heat to the contents of the latter, the finger grip or portion of the pen beyond the main barrel being left free 30 from the surrounding insulator; second, in means to close the ink feed duct to prevent the passage of ink therethrough, third to form the pen of transparent material; fourth in the parts and combination of parts 35 as will be hereinafter more fully set forth.

In the drawings:—Figure 1 is a longitudinal vertical section of a fountain pen embodying my invention; Fig. 2 is an enlarged detail section showing the ink duct 40 open; Fig. 3 is an enlarged detail sectional view showing the ink duct closed; Fig. 4 is an enlarged detail sectional view of a packing; Fig. 5 is a detail sectional view through the nib end of a pen showing an- 45 other embodiment of my invention with the feed duct open; Fig. 6 is a similar view showing the feed duct closed and the top of the pen in place; Fig. 7 is a top plan view of the feed bar; Fig. 8 is a bottom plan view 50 of the feed bar; Fig. 9 is a detail sectional view of the nib end of a fountain pen showing another embodiment of my invention with the feed duct open; Fig. 10 is a similar view showing the feed duct closed; Fig. 55 11 is a detail sectional view of a fountain pen showing another embodiment of my invention; Fig. 12 is an enlarged detail sectional view of the closure used in Fig. 11.

Referring to Figs. 1, 2, 3, and 4, the reference numeral 1 designates the main barrel or reservoir of a fountain pen and 1^a the finger grip or shaped portion beyond the same, the former portion 1 being made of two sleeves, preferably of thin transparent material with a space 2 therebetween, the 60 sleeves being sealed up air tight at each end, the final sealing being done after the air has been exhausted from the space between the sleeves, so as to maintain a vacuum. The rear end of the barrel is preferably left 65 solid for the combined purpose of spacing the two sleeves and hermetically closing the vacuum chamber at that end. The forward finger grip or shaped portion 1^a is preferably solid, except for the ink duct and other 70 passage therethrough, and serves effectively 75 for joining the front ends of the concentric vacuum chamber walls and hermetically closing the vacuum at that point. Inasmuch as the vacuum is a non-conductor, a 80 change of temperature will not pass through it, therefore the air inside of this pen will not be subjected to atmospheric changes, nor to the heat from the hand which usually 85 causes an excessive flow of ink, therefore 90 the contents of the pen remain at an even temperature irrespective of the use of the pen. The warming and consequent expansion of the contents of a fountain pen causes the feed to flow too rapidly when a person 95 starts to write with a cold pen; this overflow being the most marked and excessive when the pen is nearly full of air and the ink nearly exhausted. One of the many advantages of the transparency of the pen is 100 that the person is enabled to determine accurately when the pen needs filling and when it has been properly filled. Also one may readily locate an obstruction in the feed duct of the pen. 3 is a feed bar of ap- 105 proved construction having a feed duct 4, said feed bar being adapted to fit within the nib end of the pen in the usual manner. 5 is an opening formed transversely through the feed bar intercepting the feed duct 4. The main barrel or body 1 is provided with 110 a transverse opening 6 in one of its walls in line with the opening 5 in the feed bar but of greater diameter than the opening 5 and provided with interior screw threads, the 110 perimeter of the feed bar forming a seat at the bottom of the opening 6 on which the

base 7 of a gasket 8 is adapted to be secured by means of the annular clamping nut 8^a, said nut being adapted to engage the screw threads of the opening 6 in the barrel, 5 whereby it clamps the base flange 7 of the gasket 8 firmly on the perimeter of the feed bar, the perimeter of the base flange 7 closing the joint between the feed bar and the main barrel. 9 is a plunger having an enlarged cap head the latter being adapted to fit snugly within the opening 6 in the main barrel, the stem 10 of the plunger being adapted to work through the gasket 8 which fits it snugly to prevent leakage, the inner 10 end of the stem being provided with a collar 11 and a screw threaded shank 12. 13 is a dam secured on the screw threaded shank 12 of the plunger 9 adapted to fit fluid tight in the opening 5 in the feed bar 15. 14 is a coil spring, one end of which is seated on the clamping nut 8 and the other end under the cap head of the plunger 9 whereby, when the cap 15 is removed from the body of the pen, said plunger is forced 20 outwardly carrying with it the dam 13, thus opening the feed duct of the feed bar and permitting a free flow of ink therethrough. When the cap 15 is replaced on the body of the pen it engages the cap of 25 the plunger 9, thereby forcing the plunger downward and projecting the dam 13 into the feed duct thus preventing the flow of ink therethrough as shown more clearly in Fig. 3.

30 Referring to Figs. 5, 6, 7 and 8, 16 is the main body of the pen, 17 is a feed bar having the feed duct 18, said feed bar being provided with a longitudinally disposed slot 19 intercepting the feed duct and having upwardly converging walls, whereby the area of the slot is less at the top than at the bottom. 20 is a dam of flexible material seated in the slot 19. 21 is a plunger projecting through an opening 22 in the wall 40 of the pen body 16 with its inner end firmly secured to the bar 20. When the cap is removed from the body of the pen the parts assume the relation shown in Fig. 5, but when the cap 23 is placed upon the pen body 45 it engages the plunger 21 depressing it, thereby forcing the dam through the top of the slot into the feed duct, whereby the feed duct is closed against the passage of ink therethrough.

50 Referring to Figs. 9 and 10, 24 represents the main body of the pen. 25 is a dam of flexible material mounted on a rod 26, the outer end of which is provided with an enlargement 27. 28 is the feed duct of usual 55 construction provided with an axially disposed opening 29 in which the body of bar

26 is adapted to reciprocate. In the construction shown in these figures the flow of ink is closed off by pulling the rod 26 upwardly, thereby compressing the dam 25 between the converging walls of the nib end of the pen. 65

Referring to Figs. 11 and 12 the construction of the feed bar is like that described in connection with Figs. 9 and 10 and the general operation is the same as that described in connection with Figs. 9 and 10. The dam in Figs. 11 and 12 is composed of an annular spring 30 secured around the enlarged end 31 of the rod 32. 33 is a rubber band secured 70 on the enlarged end 31 of the rod 32 and over the compressible spring 30. The ends of the rubber band are firmly clamped on the enlarged end 31 by means of fine thread 34. Suitable fine textile material 35 is secured over the rubber band by said fine threads. The diameter of the spring is such that when the dam is drawn into contact with the converging walls of the pen body at the nib end it is compressed, thereby forming a fluid tight closure between it and the said converging walls and thus closing off the flow of ink through the feed bar. 75

The various forms of fountain pens disclosed may all be filled by placing a bulb 80 or squirt bottle over the writing end of the pen. By compressing the bulb, the ink will then be forced into the reservoir and the air out of it through the feed duct 4. 85

While I prefer to make the cap of the pen 90 of transparent material it is not necessary to do so.

I claim:—

A fountain pen comprising a main barrel and a finger grip; the main barrel being 100 constructed of two spaced walls with an ink reservoir within the inner wall and an insulating vacuum between the walls; said walls being hermetically united at their rear ends; the finger grip being substantially 105 solid, except for the ink or other functioning ducts formed therein, and being hermetically united to and forming the spacing and chamber closing means for the forward ends of the walls of the main barrel; the 110 parts being arranged substantially as shown and described to provide a vacuum insulating chamber restricted to the main barrel of the pen in rear of the finger grip.

The foregoing specification signed at Victoria, British Columbia, this 23rd day of July, 1913.

JUSTIN GILBERT.
